BOOSTER PUMP FOR HOT WATER SYSTEMS

Emil Lapp, Zurich, Switzerland, assignor to E. Lapp &
Co. A.G., Zurich, Switzerland

Application April 3, 1956, Serial No. 40,886

Term of patent 14 years

(Cl. D65—1)

Fig. 2

Des. 186,557

PAGE 2

Fig. 1 is a side view of the booster pump for hot water systems embodying my new design,

Fig. 2 is a side view with the pump turned 90° from the position shown in Fig. 1,

Fig. 3 is a perspective view of the booster pump, and

Fig. 4 is a perspective view showing the booster pump turned 90° from the position shown in Fig. 3.

I claim:

The ornamental design for a booster pump for hot water systems, as shown.
